RINSE CYLINDER FOR ATTACHMENT TO ROTARY WASHING MACHINE BASKETS

Clifford T. Maloy, Englewood, Colo.

Application April 20, 1949, Serial No. 88,512

2 Claims. (Cl. 68—148)

1

This invention relates to rinse cylinders for washing machines, and more particularly to a rinse cylinder adapted to be mounted in the drying basket of a certain type of washing machine, i. e., those models of the Easy washing machine manufactured during the years 1937 to 1947, inclusive, by the Easy Washing Machine Corporation, Syracuse, New York.

The main object of my invention is to provide a rinse cylinder which is simple in construction, economical in cost of production, self-contained in that it comprises a cylinder equipped with built-in means for supplying water directly to the cylinder from a source of supply without passing through the cover or body of the washing machine, and provided with means whereby the cylinder may be installed with ease in the drying baskets of existing washing machines of the character described.

In the drawings:

Fig. 1 is a vertical sectional view of my improved rinse cylinder, with the means for supplying water thereto broken away at the top, showing the cylinder mounted on the upper end of the rotatable hub or spindle of the drying basket of a washing machine of the type referred to herein.

Fig. 2 is an elevational sectional view, on a smaller scale, showing a drying basket of a washing machine, with my rinse cylinder positioned therein.

Fig. 3 is a transverse sectional view showing the uppermost spacer member in the rinse cylinder.

Fig. 4 is a transverse sectional view showing the intermediate one of the three spacer members.

Fig. 5 is a side elevational view of the rinse cylinder and means for supplying water thereto.

In that embodiment of the invention shown in the drawings, the rinse cylinder is indicated as a whole at 3 and the drying basket at 9. In conventional washing machines of the models referred to, the drying basket 9 is mounted on and rotatable with the rotatable member 20 in the tub of the machine (not shown). My rinse cylinder 3 is mounted on the upper portion or hub 16 of the rotatable member 20, the basket and cylinder being coaxial.

The cylinder 3 is provided at its upper end with a spacer 2, in the form of a ring, provided with a roller bearing 1 made of a plurality of ball bearings 12, said roller bearing 1 being fitted in the spacer 2 to surround a short length of hollow pipe 5 which extends from the top of the

2

cylinder through said spacer 2 and through a water seal 4 into the interior of the cylinder 3. The water seal 4 prevents water from entering the bearing member 1.

- 5 Water is supplied to the pipe 5 through an elbow 6 from a hose 7 connected to any suitable source of supply such as a household faucet (not shown), the hose 7 being connected to the elbow 6 by means of a connection 8.
  - 10 The dryer basket 9 is provided with a plurality of apertures 10 which extend through the side walls of the basket, and the cylinder 3 is provided with numerous apertures as indicated at 11 in the drawings.
  - 15 Additional spacers indicated at 14 and 18 serve to mount the cylinder on the hub 16 in the dryer basket 9. Preferably I employ set screws 13 of the Allen type, three of such screws 15 extending through the cylinder wall and spacer 14, and three of such screws 17 extending through the cylinder wall and spacer 18, to position the cylinder vertically on the hub 16 of the rotatable member 20.

Screws 19 fasten the spacer 2 to the cylinder wall adjacent the top of the cylinder.

Operation.—After clothes have been washed they are transferred to the drying basket 9, to occupy the space between the rinse cylinder 3 and side walls of the basket 9. Water is supplied from any suitable source through the hose 7, elbow 6, and pipe 5 directly into the cylinder 3, from whence it flows through the apertures 11 in the sides of the cylinder to rinse the clothes in the basket 9. The water also passes through the holes 21 in the spacers 14 and 18 so that it will emerge through the apertures 11 in the lower portion of the rinse cylinder as well as through the apertured cylinder wall above the spacer 14. The basket and cylinder preferably are rotated during the rinsing operation to cause the water to pass radially outwardly through the clothes under influence of centrifugal force.

After the clothes have been rinsed, the water supply may be cut off and the rotation of the cylinder and basket continued until the clothes have been dried to a desired degree.

From the foregoing it will be observed that I supply water directly to the rinse cylinder 3 through the stationary pipe 5 without providing water conduits which extend through the cover or body of the washing machine. This arrangement enables me to provide a low cost self-contained rinse cylinder for existing washing machines of the type described, mountable in exist-

ing machines without alteration of the cover or other parts of the machine proper.

Another important feature of the invention resides in the means for quickly and efficiently mounting the rinse cylinder and the water supply means directly on the rotated hub of existing machines of the type mentioned, without alteration or modification of said machines.

Changes may be made in the form and in details of construction of the mechanism described without departing from the scope of my invention as set forth in the appended claims.

I claim:

1. A quickly removable and replaceable self-contained rinse cylinder unit for washing machines, comprising a hollow open ended apertured cylinder, a bearing member coaxially mounted in the cylinder, a conduit for conveying water directly into the cylinder mounted in and extending through said bearing member into the interior of the cylinder, said conduit being supported solely by the cylinder and bearing, the bearing member being rotatable relatively to the conduit, and means mounted in the lower portion of the cylinder for removably and frictionally engaging a rotatable hub in the washing machine to position the cylinder coaxially on said hub. 15
2. A quickly removable and replaceable self-contained rinse cylinder unit for washing machines, comprising a hollow open ended apertured 20
- 25
- 30

cylinder, a bearing member coaxially mounted in the cylinder, a conduit for conveying water directly into the cylinder mounted in and extending through said bearing member into the interior of the cylinder, said conduit being supported solely by the cylinder and bearing, the bearing member being rotatable relatively to the conduit, a pair of vertically spaced apart spacer members mounted in the lower portion of the cylinder, and means radially adjusting the spacer members for removably and frictionally engaging a rotatable hub in the washing machine to position the cylinder coaxially on said hub.
